[57] CLAIM

The ornamental design for a bottle, as shown and described.

DESCRIPTION

FIG. 1 is a top, rear and left side perspective view of a bottle showing my new design;

FIG. 2 is a bottom view thereof;

FIG. 3 is a front elevational view thereof, the rear elevational view being a mirror image; and,

FIG. 4 is a right side elevational thereof.

The broken lines shown in the figures are for illustrative purposes only, and form no part of the claimed design.
